UNITED STATES PATENT OFFICE.

WILLCORD W. COTE, OF HOLYOKE, MASSACHUSETTS, ASSIGNOR OF ONE-HALF TO F. G. BURNHAM, OF HOLYOKE, MASSACHUSETTS.

FIRE-ESCAPE.

1,206,676.

Specification of Letters Patent. Patented Nov. 28, 1916.

Application filed December 22, 1915. Serial No. 68,231.

To all whom it may concern:

Be it known that I, WILLCORD W. COTE, a citizen of the United States, residing at Holyoke, in the county of Hampden and State of Massachusetts, have invented new and useful Improvements in Fire-Escapes, of which the following is a specification.

This invention relates to fire escapes, and one object of the same is to provide means by which escape with safety may be accomplished from a burning building through the medium of a simple and effective organization involving a rope or cable which is automatically controlled as to the pay out when the escaping person approaches the sidewalk or ground surface.

A further object of the invention is to provide a fire escape which may be easily arranged for use in connection with a window or other outlet from a building and having a rope or cable adapted to be suitably attached to the body of the user of the device and also embodying means whereby when one cable is descending another controlled by the same mechanism is ascending and being coiled ready for use by another person, with material advantages in the quick escape of a number of persons from a burning building.

With these and other objects in view the invention consists in certain novel features of construction and the combination and arrangement of parts as will be more fully hereinafter described and claimed.

In the drawing: Figure 1 is an end elevation of a fire escape embodying the features of the invention. Fig. 2 is a side elevation of the same. Fig. 3 is a transverse vertical section taken in the plane of the line 3—3, Fig. 2. Fig. 4 is a central longitudinal vertical section of the improved escape device.

The numeral 5 designates a frame constructed of suitable metal, preferably of malleable iron, and comprising end hangers 6 and upwardly projecting hooks 7 by means of which the device may be suspended from any suitable means such as cable loops, rods or analogous devices secured either permanently or temporarily to a part of a window or other outlet of a building. It is preferred, however, that any suitable form of swinging bracket be used as the attaching

means for the improved device, said bracket being hung upon eye-bolts fastened outside of a window or other opening. As this 55 bracket structure is obvious and forms no part of the invention it has not been illustrated, and it will be understood that the improved device is not confined in its application to any exact structure of suspending 60 means. The hangers 6 have their ends bored or formed with openings, as at 8, and there-in the opposite extremities of a fixed shaft or pin 9 are held and prevented from having longitudinal shifting movement by suitable 65 fastenings or linch pins 10. On the shaft or pin 9 a drum 11 is mounted, which as shown embodies two reels 12 and 13, or the drum 11 is divided so as to provide two integrally formed reels. The drum 11 is free to rotate 70 on the shaft or pin 9 and each of the reels 12 and 13 is provided with a rope or cable 14 and 15 so arranged that for instance when the cable 14 is unwinding with relation to its reel 12, the cable 15 will be winding on 75 its reel 13. The cables 14 and 15 will be of a length proportionate to the distance that the window or outlet from a building is from the pavement or ground surface so as to insure a safe descent by the user of the improved device. While two reels 12 and 13 are shown and will be preferably used, it will be understood that the drum may be of single form and thus reduced in its structure and weight to adapt it to be readily 80 carried from one place to another and operable by a single person. The double form of the improved device, however, is of comparatively small proportions and dimensions and may be readily transported from one 85 place to another and be usable by many persons in descent from a burning building for the reason that while one rope or cable is unwound the other will be wound, and this alternate operation provides for always 90 having one cable in condition for descent from a point where the improved device may be applied.

The one end of the drum 11 is formed with a series of radial flanges or projecting webs 100 16 uniformly rotating with the said drum. The flanges or webs 16 project into a metal brake drum or shell 17 which is fully open at the inner side adjacent to the end of the

drum 11 carrying the said flanges and closed at its outer side and periphery. The inner side of the periphery or rim 18 of the brake drum has a lining 19 of asbestos or other suitable material secured thereto, and between the flanges or projecting webs 16 are four cast iron or other suitable metal friction blocks 20 having considerable weight and provided with outer bearing edges 21 to contact with or firmly engage the lining 19. These friction blocks 20 are of segmental form, as clearly shown by Fig. 3, and are rotated around the fixed shaft or pin 9 within the drum 17 by the flanges or webs 16 and have a continual tendency to be thrown outwardly through centrifugal action during the rotation of the drum 11, and as the speed of the drum accelerates and reaches a maximum degree of rotation these friction blocks will be thrown out into braking engagement with the lining 19 and thereby automatically check the rotation of the drum. The brake drum 17 is held against rotative movement by two lugs 22 projecting upwardly on opposite sides of and close to the frame 5 or the main horizontal bar of the said frame, as clearly shown by Fig. 3, and by this means the loose friction blocks 20 will have a positive action relatively to the inner lined side of the periphery or rim 18 of the brake drum 17. It will be observed that the drum 11 is comparatively short, and in fact the entire improved fire escape is reduced as much as practicable so as to render the same compact without weakening the structure thereof.

One of the special features of the improved fire escape as compared to devices of this class having double drums or a single drum divided into two parts or reels is the shortening of the drum without depriving the improved device of the least efficiency in operation. In operation the cable leaves either drum at a large circumference, but as the cable nears the end of its winding on the drum the speed is lowered and the distance of travel is less, owing to the gradual diminution in the circumference at which the cable leaves the drum. Another feature is the construction of the friction blocks with extended outer friction engaging edges or faces and of the same curvature as the inner side of the lined periphery or rim 18 and whereby the friction surface is enlarged or a maximum frictional engagement is obtained between the blocks and the inner lined periphery or rim 18 of the brake drum 17. The cables 14 and 15 will be provided with suitable body attaching means whereby said cables may be securely fastened to the body of the user, preferably under the arms, so that the hands of the person escaping will be free for grasping the cable during descent. To assist in primarily winding the one cable on the drum an opening 23 is formed in the

outer end of the drum, as shown by Fig. 4, for insertion therein of a pin or other device whereby the drum may be conveniently rotated. The several parts of the improved device are also simplified and require very little machine work to prepare the same for practical service, and they may be very easily assembled and consequently the improved device can be manufactured and sold at a very reasonable cost. 75

What is claimed is:

1. In a fire escape, a suspending frame carrying a fixed shaft, a drum loosely and rotatably mounted on the shaft and having projections at one end, a brake drum also mounted on the shaft and held against rotation by a part of the frame and into which the said end projections of the rotatable drum extend, the loose rotatable drum extending over a greater portion of the shaft 80 and having the end projections only thereof located within the brake drum so that the remaining portion of the rotatable drum may be entirely clear of the brake drum, friction blocks loosely mounted in the brake 90 drum between the projections and operable to engage a portion of the friction drum, the said blocks having their side edges in loose engagement with the opposite sides of the end projections of the rotatable drum, and a 95 cable having winding association with the first named drum, the shaft also loosely extending through the brake drum.

2. In a fire escape, a suspending frame having a fixed shaft engaging opposite end portions thereof, a cable drum of less length than the frame and loosely and rotatably mounted on said shaft and provided with a cable in winding association therewith, the inner end of the drum having radial flanges 105 projecting therefrom, a hollow brake drum also mounted on the shaft and held against rotation and provided with a rim having an inner lining of suitable material, the flanges on the inner end of the rotatable drum being 110 freely movable within the said brake drum, the latter having a fully open inner end, and segmental friction blocks loosely mounted in the brake drum and held between the said radial flanges of the cable drum and by their 115 form providing extended friction edges to engage the lining of the brake drum and operating to automatically check the movement of the cable drum, the shaft also loosely extending through the brake drum. 120

3. In a fire escape, the combination of a suspending frame having a shaft disposed horizontally therein and engaging opposite end portions of the frame, a cable drum divided into two parts and loosely and rotatably mounted on the said shaft, the said cable drum being engaged by reversely winding cables and said drum also having radial flanges at the inner end, a hollow brake drum fully open at its inner end and into 130

which the radial flanges of the cable drum extend, and friction blocks loosely mounted in the brake drum between the radial flanges of the cable drum and operable to engage the periphery of the brake drum to check the rotation of the cable drum, the shaft also loosely extending through the brake drum.

In testimony whereof I have hereunto set my hand in presence of two subscribing witnesses.

WILLCORD W. COTE.
